US00D773760S

(12) United States Design Patent (10) Patent No.: US D773,760 S
(45) Date of Patent:  Dec. 6, 2016

(54) WASHING MACHINE

(71) Applicant: Samsung Electronics Co., Ltd., Suwon-si (KR)

(72) Inventors: Junghoon Hwang, Yongin-si (KR); Deoksang Yun, Ansan-si (KR); Yeonsu Kim, Seoul (KR); Wonchul Hwang, Seoul (KR)

(73) Assignee: SAMSUNG ELECTRONICS CO., LTD. (KR)

() Term: 15 Years

(21) Appl. No.: 29/537,277

(22) Filed: Aug. 24, 2015

(30) Foreign Application Priority Data

Feb. 24, 2015 (KR) 30-2015-0009299

(51) LOC (10) Cl. 15-05

(57) CLAIM

The ornamental design for a washing machine, as shown and described.

DESCRIPTION

FIG. 1 is a perspective view of a washing machine, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is an enlarged view of the portion 8 of FIG. 1;

FIG. 9 is a perspective view of a washing machine, showing our new design in another configuration;

FIG. 10 is a front view thereof;

FIG. 11 is a rear view thereof;

FIG. 12 is a side view thereof;

FIG. 13 is another side view thereof;

FIG. 14 is a top view thereof;

FIG. 15 is a bottom view thereof; and,

FIG. 16 is an enlarged view of the portion 16 of FIG. 9.

The broken lines illustrating portions of the washing machine are environmental purposes only and form no part of the claimed design.

The dot-dash broken lines encircling enlargement portions of the design form no part of the claimed design.

1 Claim, 16 Drawing Sheets
